(57) **CLAIM**

An ornamental design for a beverage bottle, as shown.

DESCRIPTION

FIG. 1 is a top perspective view of a beverage bottle; FIG. 2 is a front elevation of FIG. 1 (a side elevation and a rear elevation would be identical to the front elevation shown in FIG. 2);

FIG. 3 is a top plan view of the embodiment shown in FIG. 1; and,

FIG. 4 is a bottom plan view of FIG. 1, with the portion of the bottle shown within dashed lines forming no part of the claimed design.

The broken lines are shown in the views for illustrative purposes only and form no part of the claimed design.
